ELECTRIC BURGLAR ALARM SYSTEM

George L. Fleming, New York, N. Y.

Application September 11, 1946, Serial No. 696,131

12 Claims. (Cl. 177—314)

1

This invention relates to an alarm system; more particularly to an electrical alarm system for burglar or illegal entry detection.

It is an object of my invention to provide an alarm lock mechanism to provide an audible signal upon tampering with a door or window or like closures, which audible signal, is effective or in operation for a predetermined period of time, so that if the audible signal accomplishes its purpose of warning before unauthorized entry is effected, or serves to frighten away the prospective intruder, the audible signal will be discontinued and the annoyance of the persistent sounding of the signal obviated.

It is contemplated by my invention to provide a burglar alarm system integrating or combining an audible signal with the movement of a closure, such as a door or window, so that it will be effective upon tampering to give a signal for a predetermined period of time, whether the closure is fully opened or not, and upon the expiration of the predetermined time and renewed activity by the intruder, the unauthorized opening of the closure will again be accompanied by an audible signal.

It is further contemplated by my invention to provide a burglar alarm lock mechanism which includes electrically operated signalling circuits, one to produce an audible signal and the other to give evidence of actuation of the audible signal so that if tampering with the closure, such as a window or door, has been effected, a visual signal will be obtained, thereby making the device proof against improper setting of the audible alarm system.

It is further an object of my invention to provide an alarm lock controlled mechanism in which the audible signal is provided by an electrical circuit which is switched on for a predetermined time upon tampering, and which is discontinued to avoid the annoyance to the neighborhood if the tampering without entry or wide opening of the door or closure has been discontinued, and to combine with such mechanism a switch construction arranged so that any attempt to render the switching mechanism inactive will again actuate the audible signalling device.

Further objects of my invention residue in the provision of alarm lock mechanism which is effective to switch on an audible alarm system in several positions of the closure, such as the door or window, whereby during one position amounting to no more than tampering action, the audible signal may operate for a predetermined period of time, and during the second position, where

2

access is possible, the audible signal may be continuously effective.

Still further objects of my invention reside in the provision of an alarm lock and alarm lock mechanism which is electrically controlled to provide an audible signal and which avoids the nuisance and irritation of the audible signal in congested areas if tampering without actual access or entry has been effected.

10 To attain these objects and such further objects as may appear herein, or be hereinafter pointed out, I make reference to the accompanying drawings forming a part hereof, in which—

Figure 1 is a plan view showing my device assembled in connection with a door;

Figure 2 is a magnified plan view of the time control switch mechanism;

Figure 3 is a fragmentary section taken on the line 3—3 of Figure 2;

20 Figure 4 is a section taken on the line 4—4 of Figure 2;

Figure 5 is a fragmentary perspective view of the time control mechanism;

Figure 6 is a section taken on the line 6—6 of Figure 1;

Figure 7 is a longitudinal sectional view through the lock casing;

Figure 8 is a wiring diagram of my installation.

Making reference to the drawing, I have illustrated the same in connection with a closure in the form of a door 10, for the frame 11, on which the door is hinged by the usual hinges 12. A lock casing 13 is arranged to be operated by a turn knob 14 to project the bolt 15 into the hasp or strike 16. The bolt 15 is arranged to be operated through the cylinder 17 by a key 18 from the exterior face of the door.

The lock casing 13 has its rear wall 19 provided with insulating blocks 20, 21, supporting spring fingers 22, 23, for the cooperative contacts 24. Conductors 25 and 26 are electrically connected to the spring fingers 22 and 23, respectively. Normally, the spring fingers 22 and 23 urge the cooperative contacts into engagement. Key or knob retraction of the bolt 15 serves to move the yoke 27 rearwardly of the casing. The yoke is provided with a lug 28, moving in the path of the spring finger 23, to deflect it rearwardly and break the contacts 24 from engagement, electrically opening the circuit in the conductors or wires 25 and 26 of the switch. The mechanism of the lock casing 13 accordingly acts as a switching mechanism, to electrically open or close a circuit of which conductors 25 and 26 are a part.

Conductor 25 is connected to one terminal of

the secondary S of the transformer T whose primary terminals P, by suitable plug connectors, lead to a source of A. C. power 29.

Conductor or wire 26 is grounded to the bracket 30, which carries a plunger 31 within the sleeve 32. One end 33 of the plunger is spring projected into the inner face 34 of the door frame. The other end 35 has a contacting head 36 which may ride in the path of the contacts 37 and 38, respectively. Contacts 37 and 38 are insulated from each other and supported on the bracket 39. Conductors 40 and 41 are connected to the contacts 37 and 38, respectively. Conductors 40 and 41 complete the circuit to the time control switching assembly 42, which will hereinafter be described.

For present purposes it will be sufficient to indicate the operation of the switch assembly carried by the bracket 30. With the door 10 closed, the nose 33 is depressed to the inner face 43 of the door frame 44. In this position the head 36 clears the contacts 37 and 38. As the door swings open partly, the spring in the cylinder 32 projects the plunger for a distance to bring the head 36 into wiping action with the contact 37. Under these circumstances, the circuit is closed in the line 26 and the line 40. If the door should swing further, the plunger nose 33 follows the edge of the door 10, to spring project the contacting head 36 in wiping engagement with the contact 38, closing the circuit of the line 26 and the line 41.

An auxiliary head 36a is mounted on the plunger 31. Should any instrument be pried in between the door edge and the frame to depress the nose 33 or to spring the frame to depress the auxiliary head 36a, the circuit through the lines 26 and 41 will be completed through the auxiliary head 36a and the contact 38.

In the time control switching assembly 42 there is provided a chamber 45, within which rides the piston 46. The piston rod 47 is guided in the neck 48. An expansion spring 49 acting between the neck 48 and the piston 46 normally tends to urge the piston toward the head 50. A port 51 is controlled by a screw adjustable needle valve 52 which is adjustable through the knurled head 53. The port 51, on its exterior side, leads out to the atmosphere through the vent 54.

It will be observed that as the piston 46 is retracted manually against the spring pressure of the spring 49, it will return to its projected position at a rate of movement determined by the position of the needle valve 52 closing the port 51. Thus, the duration of time may be measured off predeterminedly after retracting the piston 46 manually to control movement of the piston 46 to the expanded position of the spring 49. This action is controlled as to time by the rate of escape of air through the port 51.

The piston rod 47 is connected to an extension shaft 55. The extension shaft 55 is guided in a guide slot 56 in the casing wall 57 and is manually operable by the knob 58 to retract the piston 46 in its cylinder 45. The extension rod 55, on its inner end, is guided on the spaced arms 59 between which there rides the latching bar 60 pivoted by the pivot pin 61.

The extension rod 55 is guided on the shoulder 62 and against the front edge 63 of the latching bar 60. A spring 64 has one end anchored to the casing of the switching assembly 42 and its opposite end to the pivot point 65, thus normally urging the edge 63 against the extension rod. The extension rod has a shoulder 66 which may

lock behind the front edge 63 when the extension rod has been pulled outwardly against the spring pressure of the spring 64. In this position the latching bar 60 engages the shoulder 66, preventing spring retraction of the extension rod.

The locking bar 60 has its upper end 67 spaced opposite a tripping finger 68, carried by the armature 69. The armature is positioned for movement to be actuated by the electromagnet 70. Conductors 40 and 60a provide the circuit for energizing the electromagnet 70, to draw the armature to the core thereof.

It will be observed that when the piston 46 is held actuated by the engagement of the shoulder 66 against the latch bar 60, activation of the electromagnet 70 will draw the armature 69 toward it, carrying with it the tripping finger 68, to strike the latch bar 60 and move it rearwardly out of engagement with the shoulder 66, permitting spring projection of the piston 46 and carrying with it, at a time controlled rate, the extension rod 55.

The rod 55 adjacent its shoulder 66 carries a resilient bar 71 against a switch block 72 in line with a pair of switch points 73 which actuates spring leaves 74 and 75. When the latch bar 60 has been moved to its unlatching position of the extension rod 55, for purposes hereinafter to be described, it carries the bar 71 in its limiting position adjacent the lock 76 where it engages the trip finger 77 bearing against the plate 78 carrying contacts 79 cooperative with the spaced contacts 80 and 81.

Conductors or wires 82, 83 and 84 combine with the switch contacts 73' and 75 to serve in closing the circuit for the visual signal or light 85. This occurs at any time the bar 71 moves from holding position.

Conductors 86 and 87, controlled by the switch contacts 73 and 74 activate the audible signal, in the form of an electromagnetically operated bell or gong 88, in one position (pulled out) of the manually controlled piston 46. The circuit is completed through the conductor 89, leading to the line or conductor 90 and connected with line 26. When the bar 71 moves to contact the switch finger 77, it closes the bell circuit again in moving the bar 71 carrying spaced contacts into engagement with the contact 80, which is connected by the conductor or wire 91 to the conductor 41 and thence through the contact head 36 and its wiper to the line 26.

The operation of the device is as follows:

Preliminarily the occupant of the premises pulls the knob 58 to set the device. This manual pulling of the extension rod 55 to its full limit draws the same to the point where the shoulder 66 is latched in the withdrawn position by the latch bar 60. This action opens the circuit for the bell or gong 88. This action also brings the circuit for the visual signal, in the form of a lamp 85, to the open position.

Upon turning the knob 14 or the key 18 to project the bolt 15 into the hasp or strike, the circuit controlled by the normally engaging contacts 24 is closed, as the contact of the leaf spring 23 is permitted to move to the closed position by reason of the extension 28 having been withdrawn.

The frame switch assembly carried by the bracket 30 and controlled by the nose 33, upon the closing of the door, has also been moved to the open position. Should entry be attempted by forcing of the closure or door 10, the first movement thereof for a small fraction of the distance

of the door will cause the nose 33 to follow in the frame 44. In doing so, the contact 36 will engage the contact 37, activating the electromagnet 70. This sets in motion the latch bar 60 as the armature is drawn towards the electromagnet. The action of the spring 49 against the piston 46 drives the extension rod 55 from its cocked position. The preliminary action is to release the cross bar 71, permitting the switch contacts 73, 74, 73' and 76 to move to the closed position, thereby closing the circuit for the bell or gong, giving the audible signal and closing the circuit for the visual signal of the light 85.

The extension rod and its assembly carried on the rod 47 are urged to the closed position by the spring 49. Air escapes through the port 51 at a controlled rate, determined by the position of the needle valve 52. Should the intruder be frightened away at this stage, the audible signal will continue as long as the cross bar 71 is moving between the switch block 72 and the switch block 76. If no further movement of the door has been effected than the distance of the setting between the head 36 and the contact 37, upon the bar 71 urging the switch block 76, it will engage the switch finger 77 and break or open the bell circuit. The light circuit, however, has been completed and maintains its visual signal. This visual signal is an indication that tampering has occurred, even though the attempted intruder is unsuccessful or has been frightened away.

Should the door or closure be completely opened to permit the nose 33 to progress by spring action from the position where the contact head 36 clears the contact 37 and then contacts the second contact 38, the circuit through the conductor 41 and the contact 80 will be closed to the bell or gong, again to activate this audible signal.

If during the initial action by the intruder, any endeavor is made to spring or force the frame 44 to reach the nose 33 and render it inactive, slight movement of the nose 33 will serve to direct the auxiliary head 36a into engagement with the contact 38, to close the circuit for the bell or gong 88. Key operation of the lock to retract the bolt 15 and set the extension 28 against the spring leaf 23 will serve to open the circuit for the bell, while leaving the circuit for the light 85 closed. This is an indication to the occupant of the condition of the setting of the burglar safety mechanism. If the light signal is on, evidence of tampering is shown, as previously mentioned. If it is in the "off" position, or not burning, no further attention need be given to the manual setting of the device controlled by the knob 58.

Entrance key operation in retracting the bolt 15 to cause the extension 28 to break the circuit controlled by the contacts 24 renders the bell circuit 88 inactive, while leaving the visual signal active if and as the manual control element in the form of the extension rod 55 has not been withdrawn. The light signal accordingly is a reminder to the occupant to set the main signaling mechanism to the active position before he leaves the premises.

It will thus be observed that I have provided an alarm mechanism controlled by the lock mechanism, which has the desirable features of supplying an audible signal of predetermined duration, so that the annoyance of the persisting audible signal may be obviated in the event that this audible signal has served the purpose of

frightening away an attempted intruder. The mechanism combines the feature of becoming active if after a predetermined period the intruder persists and has forced the closure sufficiently to move it past the auxiliary switch point, whereupon the device includes mechanism for providing a continuously effective audible signal.

While I have shown an alarm lock mechanism which, in its illustrated form, combines the various features outlined, it is understood that novelty is attributed to the separate elements and they may be used independently. Therefore, my invention is not to be limited except by the scope of the appended claims.

Having thus described my invention and illustrated its use, what I claim as new and desire to secure by Letters Patent is:

1. In an alarm mechanism for closures or the like wherein a closure frame switch is movable,

upon movement of the closure and frame relatively to each other, to make and break an electrically operable audible alarm and circuit means therefor, the combination therewith of an auxiliary switch having a pair of contacts and a power driven member having a connection for moving one of said contacts to the closed position a switch for said alarm circuit, a latch for holding said member against retraction by the power means therefor, an electromagnet for releasing said latch having a circuit connected with the frame switch and means for regulating the rate of movement of said member whereby a controlled time for the maintenance of the audible alarm may be effected.

2. In an alarm mechanism for closures or the like wherein a closure frame switch is movable upon movement of the door and frame relatively to each other, and having an electrically operable audible alarm and circuit means therefor, the

combination therewith of an auxiliary switch having a pair of contacts, one of which is operable for movement by a spring retractile member serving to close the switch contacts for said alarm circuit, a latch for holding said member against retraction, manual means for setting the member and to space the contacts and to open the switch for said circuit, an electromagnet for releasing said latch having a circuit connected with the frame switch and means for regulating the rate of retraction of said member to time the duration of said audible alarm.

3. In an alarm in accordance with claim 2 wherein said spring retractile member acts upon a piston which moves within a cylinder including a needling metering member to control the air discharged from said cylinder by said piston to time the duration of said audible signal.

4. Alarm mechanism for closures or the like wherein a closure frame switch is movable upon movement of the closure and frame relatively to each other, the combination wherein an electrically operable audible alarm and circuit are connected with said switch and include a current source therefor, an auxiliary switch having a pair of contacts and a power driven member having a connection for moving one of said contacts to the closed position, a switch for said alarm circuit, a visual signal and a circuit therefor controlled by the frame switch, a latch for holding said member against retraction after manual setting thereof, an electromagnet for releasing said latch having a circuit connected with the frame switch and means for regulating the rate of retraction of said member to control the duration of said audible alarm, said frame switch having a secondary cir-

cult connected with said audible alarm to close the circuit for said audible alarm upon expiration of the predetermined time whereby movement of the closure to a secondary position will maintain the operation of the audible alarm.

5. An alarm mechanism for closures or the like wherein a closure frame switch has contacts, one of which is movable upon movement of the closure and frame relatively to each other, the combination comprising an electrically operable audible alarm, a circuit therefor including a current source connected to the contacts of said frame switch having contacts, an auxiliary switch for the circuit of said alarm, means for manually setting a piston member having a connection operating one of the contacts of said auxiliary switch, spring means for retracting said member for operating the contact of the switch for said alarm circuit, a cylinder within which said piston member moves and an air controlling pin to regulate the rate of retraction of said piston member and thereby control the duration of said alarm.

6. Alarm mechanism in accordance with claim 5 wherein said frame switch includes a plurality of contacts, each independently controlling separate circuits, one circuit of which includes a visual signal, and switching means therefor to close the circuit upon movement of said manually settable switch.

7. Alarm mechanism in accordance with claim 5 wherein said frame switch cooperates with a plurality of contacts, each controlling independent circuits, an electromagnet in one of said circuits, a light source in another circuit, an alarm by-passed circuit whereby movement of said frame switch inwardly or outwardly of the frame may close the circuit for said audible alarm.

8. Alarm mechanism for a closure having, in combination, a key operated switch, a circuit therefor connected to a source of current, a frame switch for closing the circuit having a plurality of cooperating contacts one of which is mounted upon means controlled by different positions of the closure, an audible signal, different circuits for each of the contacting positions of the frame switch connected with said audible signal, means connected with said circuits for closing the circuits in more than one position, means for setting said last named means including latching means to hold said setting means in position, electrically responsive operable means for said latching means and a circuit for said operating means connected with the frame switch contacts, said switch setting means having a time controlled movement upon release of said latching means.

9. Alarm mechanism for a closure having, in combination, an audible alarm, a circuit for said alarm connected to a source of current therefor, a closure frame switch having a plurality of contacts one of which is mounted on means controlled by different positions of the closure for setting said alarm into action, a switch for the circuit having contacts controlled by said frame switch, means for moveably mounting the contacts of said last mentioned switch including latching means

therefor and means for restraining the setting means in accordance with some predetermined time controlled movement.

10. Alarm mechanism for a closure having, in combination, a key operated switch, a circuit therefor connected to a source of current, a closure frame switch having a plurality of cooperating contacts, one of which is mounted upon means controlled by different positions of the closure, an audible signal alarm associated with said circuit, means for moveably mounting contacts forming a switch for said circuit, a setting device for the contacts of said switch including resilient means for moving said setting device to one of two positions, means for latching said setting device, electromagnetically operable means for said latch controlled by said frame switch, and time controlled means for restraining the movement of said setting device.

11. Alarm mechanism for a key and lock controlled closure having, in combination, a circuit connected to a source of current, means to mount contacts comprising a closure frame switch, an audible alarm signal, a visual alarm signal, independent circuits for each of said signals, switch contact setting means for said circuits restrained by spring means, latching means for said setting means including an electromagnetically operable device in the circuit of said contacts of said frame switch, and means to restrain the movement of said setting means from the latched to the normal position, whereby the audible alarm signal may be maintained for a predetermined period of time.

12. Alarm mechanism for a key and lock closure comprising, in combination, a frame switch having contacting means in different positions of the closure, a circuit for said switch, said contacting means being mounted to be effective to close the circuit in said different positions an audible alarm associated with said circuit, a source of current for said circuit, a secondary switch having contacts and means to normally maintain the same closed position, latching means to maintain said secondary switch contacts open, electromagnetically operable means for said latching means, a circuit for said electromagnetically operable means controlled by said frame switch contacts and air controlled escapement means for said secondary switch closing means to time the movement of said secondary switch setting means to the normal position.
